* cited by examiner

(73) Assignee: **Roland Corporation, Osaka (JP)**

Primary Examiner—Adir Aronovich
(74) Attorney, Agent, or Firm—Foley & Lardner

(**) Term: **14 Years**

(57) **CLAIM**

(21) Appl. No.: **29/128,639**

The ornamental design for an electronic percussion instrument, as shown and described.

(22) Filed: **Aug. 29, 2000**

DESCRIPTION

(51) LOC (7) Cl. **17-04**

FIG. 1 is a right side view showing our design.

(52) U.S. Cl. **D17/22**

FIG. 2 is a bottom view thereof.

(58) Field of Search D17/22, 99; D21/405;
84/411 R, 723-733, DIG. 24

FIG. 3 is a top view thereof.
FIG. 4 is a top front/right-side view thereof, rotated approximately 45° about the horizontal axis and approximately 30° about the vertical axis with respect to FIG. 3.

(56) **References Cited**

FIG. 5 is a front view thereof.

U.S. PATENT DOCUMENTS

FIG. 6 is a back view thereof; and,
